UNITED STATES PATENT OFFICE.

RENE D. GROVE, OF MIDDLETOWN, PENNSYLVANIA.

JOINTED TOY FIGURE.

Application filed February 3, 1923. Serial No. 616,724.

To all whom it may concern:

Be it known that I, RENE D. GROVE, a citizen of the United States, residing at Middletown, in the county of Dauphin and State of Pennsylvania, have invented certain new and useful Improvements in Jointed Toy Figures, of which the following is a specification, reference being had to the accompanying drawings.

This invention relates to toy figures, and particularly to jointed figures.

The object of the invention is to provide a figure of this character having a body, limbs and head, the limbs being formed of sections elastically connected to each other and to the body in such manner that the sections of the limbs may be turned into a plurality of angular relations to each other and to the body, the head being also so elastically connected to the body that it may be turned into a plurality of angular relations to the body.

A further object is to provide a construction of the character just described wherein the sections of the limbs are not only shiftable into angular relations to each other and the body but rotatable with relation to the axis of the sections, and wherein the head is likewise rotatable with relation to its axis as well as angularly adjustable.

Still another object is to provide a construction of this character wherein the figure comprises a body, legs, arms and feet, the legs and arms being formed of a plurality of sections elastically connected to the body by elastic members extending through the axes of said sections whereby the sections may be turned into angular relation to each other and to the body and also rotated around said axes.

A further object in this connection is to provide a figure having a body and a head elastically connected to the body and adjustable into angular relation to the body and also rotatively adjustable around the axis of the head, the head supporting the similitude of a hat which is likewise adjustable into angular relation to the axis of the head and into a plurality of positions.

Still another object is to provide a figure toy of this character so formed that it will maintain its equilibrium when the arms, legs and other parts are adjusted into a large number of different positions.

Other objects will appear in the course of the following description.

My invention is illustrated in the accompanying drawings, wherein:

Figure 1 is a perspective view of a figure constructed in accordance with my invention but showing the elastic connecting members 11, 21 and 26 as being stretched so that the sections of which the figure is composed are separated;

Figure 2 is a vertical fragmentary sectional view through the figure taken transversely thereof and showing the elastic members stretched and the parts separated;

Figure 3 is a transverse fragmentary sectional view through the figure, showing the manner in which the legs are held to the body;

Figure 4 is a section on the line 4—4 of Figure 3;

Figure 5 is a perspective view of a series of these toy figures, showing the different positions which the figures may take;

Figure 6 is a perspective view showing further positions of which the figures are capable;

Referring to these drawings, and particularly to Figures 1 to 4, 10 designates the body of the toy which, as illustrated, is cubical in form and may be of wood, though it might be made of any other suitable material. Extending transversely and loosely through the upper portion of the body is an elastic cord 11 having its ends projecting beyond the sides of the body 10. The arms of the figure are formed of a plurality of sections, the sections being illustrated as two in number and designated 12 and 13 respectively. Each section 12 is preferably square in cross section and each section has divergently inclined ends 14. The forearm of the figure is formed by the section 13. This section has its upper end adjacent the end of the arm at right angles to the axis of the section, but its lower end is inclined to the axis of the section so as to abut against the inclined face 14. The elastic cord 11 passes through the axes of the sections 12 and 13 of the arm and through a block 15 which constitutes the hand of the figure. This block is oblong in form and the elastic cord 11 passes through this block and is attached thereto in any suitable manner. Preferably the bore through which the

80

100

105

elastic cord passes is disposed nearer one end of the block than the other so as to give the block, when turned, the general similitude of a hand.

5 Each leg of the figure is also constructed preferably of two sections 16 and 17, each of these sections being square or rectangular in cross section. These leg sections 16 and 17 both have their opposite end faces disposed at an inclination to the longitudinal axis of the section, and abutting against the under end face of the lowermost section 17 is a foot section 18 which is composed of a block of wood oblong in form. The lower 10 end of the body 10 is formed with a transverse, relatively deep kerf or groove 19 (see Fig. 3) which opens upon the side faces of the body at the lower end thereof and extends upward from the lower end of the 15 body. Intersecting this groove 19 are two grooves or kerfs 20 which open upon the under end of the body. An elastic cord 21 is initially disposed within the kerf 19 against the bottom thereof and then a wedge 22 is driven into the kerf 19, this wedge being equal to the distance between the kerfs 20. This wedge holds the middle portion of the cord 21 in place. The ends of the elastic cord 21 extend axially through 25 the sections 16 and 17 and through the foot section 18 and the end of the cord at the foot section is knotted and disposed in a recess on the under face of the section just as the cord 11 is knotted at its extremity and 30 disposed in a recess in the under face of the hand section 15.

It will be seen that by this construction the cord 21 may extend out through the ends of the kerf 19 or the ends of the cord may 40 be extended through the kerfs 20, these kerfs 20 extending from the front to the back of the figure. Thus the legs of the figure may be disposed to extend downward from the lower end of the body or extend forward 45 from the body, laterally from the body, or rearward from the body. The sections composing these legs may be turned with relation to each other. Thus, for instance, the sections 16 and 17 may be so turned that the 50 axial center of the legs extends downward and outward from the central vertical axis of the body, or the upper section 16 may extend downward and outward, while the lower section may extend downward and inward, downward and rearward, or downward and forward. Likewise the upper section 55 may be turned so as to extend downward and rearward, downward and forward, or downward and laterally in either direction. Each leg is, of course, entirely independent of the other leg so that the legs may be caused to assume almost any position they would take in nature. The feet rest firmly upon the ground and, of course, may 60 be turned so that the foot extends rear-

ward, laterally or forward as desired at any angle. If the ends of the cord 21 are disposed to pass through the ends of the kerf 19, then the legs will be disposed so that they will extend more or less horizontally laterally in opposite directions or one leg may extend horizontally rearward and the other leg horizontally forward, or both legs may be extended forward or both rearward.

75 The arms composed of the sections 12 and 13, while they do not have the same extent of movement as the legs, have sufficient movement so that they can be placed in positions very analogous to the positions 80 taken by the human arm. Thus, for instance, the sections 12 and 13 may be so turned that the section 12 extends downward, laterally and downward or laterally and forward, and the section 13 may be so turned with relation to the section 12 that the forearm of the figure will extend downward and forward, downward and laterally in line with the section 12, or downward 85 parallel to the side face of the figure, or downward and rearward, and the hand sections 15 may be likewise turned so that the hand may extend in any desired direction. The two arms are, of course, independently 90 adjustable with relation to each other and thus the arms may be disposed in very ludicrous and amusing positions which have a considerable similitude to life.

95 The head 23 is preferably formed of a four square block of wood or like material, the upper end of which is kerfed preferably transversely, as at 24, and the upper lateral corners of the head are beveled off, as at 25. An elastic cord 26 is attached to the upper end of the body by placing the end of the cord in a hole in the body and then driving in a wedge 27 to hold the cord in place. This elastic cord passes freely through the head 23 and into a block 28 having the similitude of a hat and having a flat under 100 face which can rest upon the upper end face of the head. The cord passes entirely through this block 28 and the upper end of the cord is knotted and disposed in a recess 105 29. Thus the hat may be shifted laterally 110 across the head and when the hat is so shifted laterally it may be tilted so as to bear against the beveled face 25 and the hat will then be apparently supported on the 115 side of the head in a cocked position.

120 Disposed between the head and the body is a neck section 30 which is formed of a relatively short block of wood, square in cross section, the under face of which is at right angles to the axis of the block, while 125 its upper face 31 is beveled. The cord 26 passes loosely through this block. By turning the block around the axis formed by the cord, the beveled faces 31 will support the head in various positions where the axis of 130

the head is inclined with reference to the axis of the body. This block 30 is preferably painted white so as to simulate a collar and by this means the head may be 5 tilted laterally, forwardly or backwardly.

The front of the block is, of course, painted to simulate a face. The arms and legs may be gaily painted and the body painted to simulate a coat or other garment 10 so that the figure forms a ludicrous caricature of a man.

It will be seen that all of the limbs of the figure are to be made of blocks having ends which are angular with relation to the 15 longitudinal axis of the block. This applies to the blocks 12, 13, 16 and 17, and the blocks 16 and 12 have their ends disposed in angular relation to the abutting face of the block 10 with which they come in contact so that these limb sections, while they 20 may be disposed in longitudinal alignment with each other, will always be disposed in angular relation to the longitudinal axis of the body 10. This adds to the grotesqueness 25 of the figure and to the ludicrous character of the positions taken by the arms and legs.

Attention is also called to the fact that these angular faces are equal to the cross 30 sectional area of these leg and arm sections so that one member in all positions abuts firmly against the adjacent member and there is no opening up of the joint no matter in what angular relation the two adjacent sections are disposed to each other or 35 disposed with relation to the body. Of course, inasmuch as the sections are rotatably mounted upon the connecting rubber band 11 or 21, the sections may be rotated with relation to each other and with relation 40 to the body so that all sorts of positions may be taken by the arms, legs and feet. The collar section 30 being beveled upon one face and being rotatable round the central rubber band, may be disposed so as to incline the head in any direction 45 and at any desired angle to the body, which adds much more to the expressiveness of the head. The hands and feet are formed of flat blocks of wood and as a consequence 50 one figure may be mounted upon the other, as illustrated in Figure 5 or Figure 6. This would not be the case unless such blocks were used for the hands and feet.

As illustrated in Figures 5 and 6, these 55 figures may be associated with each other and placed one either on the upraised hands of the lowermost figure or on the shoulders thereof, the top of the block being flat so that the feet of one figure may be placed 60 upon the shoulders of the subjacent figure.

While I have illustrated all of the sections 65 of which the figure is composed as being rectangular in cross section, I do not wish to be limited to this as obviously the sections might be rounded or formed more

closely to simulate the actual members of the human body. Neither do I wish to limit myself to figures simulating human figures, as it is obvious that the same principle might be applied to the construction of figure toys 70 simulating animals or birds, reptiles, fowl and insects. It is obvious that many changes might be made in the details of construction and arrangement of parts and the materials without departing from the spirit 75 of the invention as defined in the appended claims.

I claim:—

1. A toy figure comprising a body and a head section, an elastic member anchored 80 within the body and the head section and drawing said sections together, and an intermediate section between the head and body having a bore through which the elastic member passes and around which it is 85 rotatable, said intermediate section having its upper and lower faces disposed at different angles to the axis of the section whereby said intermediate member may be shifted to incline the head into various angular relations to the body.

2. A toy figure including a body rectangular in cross section, a head and limbs, each formed with a plurality of sections, elastic cords passing through the body and axially 95 through the sections of each limb and elastically connecting the limb sections to the body, an elastic cord connecting the head section of the body, the head sections and limb sections being rotatively adjustable 100 around the corresponding elastic cord, the limb sections being rectangular in cross section, the confronting end faces of certain of the limb sections and the faces of the limb sections confronting the body section being 105 angular relative to the longitudinal axis of the limb sections, certain of the limb sections having end faces which are angular to the longitudinal axis of the section but convergent with relation to each other, the body at 110 one end having transverse and longitudinally extending intersecting kerfs opening at their ends upon the faces of the body, the elastic cords extending from the intersection of the kerfs whereby the limb sections may 115 be disposed in angular relation to any three of the adjacent faces of the body section.

3. A toy figure including a cubical body approximately rectangular in cross section, the lower end of the body being formed with 120 a pair of kerfs extending from front to rear and a kerf extending transversely of the body, elastic cords extending from the intersections of the first named kerfs with the second named kerf, a plurality of leg sections through which the elastic cords axially 125 pass, each leg section having its ends parallel but at an acute angle to the longitudinal axis of the section, arms disposed to extend from the sides of the upper portion of the 130

body, each arm consisting of a pair of sections, the inner section having its end faces disposed in convergent relation and at an acute angle to the longitudinal axis of the 5 section, the end section of each arm having its upper face at an acute angle to the longitudinal axis of the body and its lower face at right angles thereto, flat-faced blocks disposed at the ends of the end sections of the 10 arms, an elastic cord passing through each of said blocks and passing through the sections of the corresponding arm and joining these sections to the body, flat-faced blocks disposed at the lower ends of the lower leg 15 sections and connected to the said elastic cords of the leg sections, a head, a collar section disposed between the head and the body and having relatively converging end faces, an elastic cord passing through the collar 20 and connecting the head to the body, the head being rotatable upon said cord as an axis, the confronting faces of both the leg and arm sections being of duplicate size and cross section to thereby apparently maintain 25 continuity of the surface of the limb sections in all rotative and angular adjustments of the limb sections.

4. A toy figure including a cubical body having a transverse bore adjacent its upper 30 end and a vertical bore, the lower end of the body being provided with two kerfs extending from front to rear and a single kerf ex-

tending transversely and intersecting the first two kerfs, an elastic band passing transversely through the bore in the upper portion of the body, limb sections through which the band passes, the band being connected to the terminal intersections, certain of the limb sections having faces disposed at an angle greater than a right angle relative to the longitudinal axis of the section, a head having a transverse kerf upon its upper surface, a collar disposed beneath the head and having two upper and lower converging faces, a rubber band passing loosely through the collar and through the head, a hat with which the elastic band is engaged, the head being formed with cut-off corners whereby the hat may be disposed at an angle, the elastic cord extending into said transverse kerf whereby the hat may be laterally shifted, an elastic band extending transversely through the single kerf in the lower portion of the body, means holding the middle of this elastic band from movement, a plurality of leg sections through which the elastic cord axially passes, the leg sections having their end faces disposed at an angle less than a right angle to the axis of the section, the ends of the elastic band being shiftable into either of the kerfs.

In testimony whereof I hereunto affix my signature.

RENE D. GROVE.
